SHAPING MACHINE

Application filed October 24, 1927. Serial No. 228,203.

This invention relates to machines useful in shaping articles such as heels for ladies' foot-wear more particularly of the type known as "French" heels. Such heels are now invariably made of wood, and formed, at the top or region where attachment is to be made with the shoe proper, with integral forwardly-projecting breast shanks. For the sake of neatness in appearance, the under surfaces of the breast shanks are usually rounded convexly; while some styles require counter-rounding or concaving of the inner faces of the heels with uniform mergence at the juncture of the opposing curvatures. The shaping of heel breasts of the specific character referred to is therefore quite involved and, heretofore, necessitated the use of at least two separate machines which entailed loss of time in the transfer of the heel blanks from one machine to another and added considerably to the cost of the product.

The object of my invention is to overcome the above difficulties through provision of a simple and reliable machine wherein shaping of differently configured curved surfaces or curved and flat surfaces uniformly merging, or of continuing curvature throughout the breast and shank, as instanced in connection with ladies' shoe heels, may be expeditiously accomplished in one operation.

Other advantages inherent to my invention will be manifest from the detailed description which follows when taken in connection with the drawings, whereof Fig. I is an illustration partly in side elevation—and partly in section—of a heel shaping machine conveniently embodying my invention.

Fig. II is a front elevation of the structure, as viewed from the right of Fig. I.

Fig. III is a plan view of the machine.

Figs. IV and V are detail sections, taken as indicated respectively by the arrows IV—IV and V—V in Fig. I, showing important structural features of the holding means for supporting the heel blanks incidental to shaping.

Fig. VI is a view showing the details of the lower clamp jaw of the blank holding means.

Fig. VII is a view looking from the right of Fig. VI.

Fig. VIII is a detail elevation, viewed as indicated by the arrows VIII—VIII in Fig. I.

Fig. IX is a detail view of the upper clamp jaw of the blank holding means, taken as indicated by the arrows IX—IX in Fig. I.

Fig. X is an illustration, similar to Fig. I, showing a modified embodiment of my invention.

Fig. XI is a perspective view of a wooden blank suitable to the fashioning of a shoe heel; and,

Figs. XII and XIII show two different types of heels which can be shaped with the machine of my invention.

With detailed reference first, more particularly, to Figs. I—III of the illustrations, it will be noted that the machine comprises a vertical spindle 14 which is supported for rotation in upper and lower bearings 15, 16 respectively, of the machine frame 17, and driven—in the direction indicated by the arrow in Fig. III—by a belted pulley 18, fixed to the spindle 14 in the interval between the bearings, aforesaid. At the top, the spindle 14 carries a cutting tool 19 which, in the present instance, embodies two similar profile cutting blades 20, 21 having cutting edges 20 x , 21 x and 20 y , 21 y at an angle to each other and both inclined to the horizontal. These profile blades 20, 21 are secured between collars 22, 23 having slots to receive the parallel upper and lower blade edges, the assemblage being clamped together by a nut 24 engaging the screw threaded upper end of the spindle 14.

The machine of Figs. I—III can be used in making either of the types of heels H, H' shown respectively in Figs. XII and XIII although it is more especially designed for production of heels of the first designated variety. The heel H depicted in Fig. XII is characterized by having its integrally-formed breast shank S convexly rounded as at R, and its inside surface differently configured, i. e., oppositely curved or concaved as at C, the two surfaces merging smoothly within the crotch of the bight or angular cut

at A. The wooden heel blank B, from which the heel H or H' is made, is shown in perspective in Fig. XI, the same being roughly cut to approximate the configuration ultimately desired, and provided in its lower face with a longitudinal aligning groove G which facilitates positioning in the machine and re-aligning in another machine for subsequent shaping or rounding the outside of the heel, as well as for other operations necessary to finishing.

The means for manipulating the heel blank B relative to the cutter 19, during the shaping operation, includes a carrier arm 25 which is swingable horizontally by virtue of being fixed to a vertical axis 26. This axis 26 is supported in integral bearings 27, 28 of a slide 31, which fits a vertical guide groove 32, in the frame 17 of the machine, and said slide is adjustable up and down by means of a hand screw 33, rotatable in a lateral projection 34 of the machine frame 17 and engaging the lower bearing 28, see Figs. I and II. Bolts 29, passing through slots 30 in the slide 31, serve as a convenient means for securing the latter in adjusted positions. Fastened to an integral pad 36, at the top of the carrier arm 25, is a plate 37 formed with an apertured boss 38 which is fixed to the axis 26 at the upper end, and which rests upon the top of the bearing 27, as best seen in Fig. II. The carrier plate 37 is thus virtually made a part of the carrier bracket 25 and is therefore obliged to move with it and the slide 31 during adjustment of the latter, as above noted. To facilitate such adjustment, the slide 31 is provided with an index 39 for co-ordination with graduations 40 along one edge of the slide groove 32, see Fig. II. The carrier plate 37 also has a lateral extension 41 equipped with a handle 42 by which it may be manually swung about the axis 26 for a purpose later on explained, the inward movement being limited by a stop 43 secured by means of bolts 44 to the machine frame 17, see Figs. II and III. At its top, the carrier plate 37 is provided with a guideway 45 to receive a carriage 46 which may be adjustably set along said guideway in accordance with graduations shown at 45a, Fig. III, by means of clamp bolts 47 passing through elongated slots 48 in said plate. As shown in Fig. I, the carriage 46 provides a bearing 50 that supports a shaft 51, with capacity for both rocking and axial movement, at an inclination substantially parallel to the lower edges 20y, 21y of the cutter blades 20, 21, said shaft carrying at its outer end an actuating member 52 equipped with a handle 53. The actuating member 52 is keyed to the obliquely supported rock shaft 51 at 55, and is retained against displacement through the medium of a collar 56 which is secured by a screw bolt 57. Rocking movement of the shaft 51 is limited through co-operation of a pin 58, on

the actuating member 52, with stops 59, 59a at opposite sides of the bearing 50, see Figs. I and II. The actuating member 52 has a downward arm 60 whereof the lower end is suitably configured to retain and guide a slide piece 61, which is fixable in adjusted positions by a clamp bolt 62 and carries a roller 63 that runs against a plate 64 fastened to the carriage 46. From Figs. II and VIII it will be observed that the plate 64 has a cam depression 65 adapted to be overtravelled by the roller 63 with impartation of axial sliding movement to the shaft 51, for a purpose also set forth hereinafter. At its inner end, the inclined shaft 51 has a head 66 which, as shown in Fig. IV, is reduced in thickness as at 67, with provision of a tongue to fit between the side cheeks 68 of a member 69 constituting part of a means 70 by which the heel blanks B are sustained and manipulated relative to the cutter 19 during shaping. Bolt and slot connections at 71, 72, respectively, enable adjustment of the member 69 relative to the head 66, graduations 73—Fig. I—being provided as an aid to this end. Side play between the head 66 and the member 69 is prevented through rabbeted engagement of a guide block 74, secured in the interval between the side cheeks 68, with the inner end of the tongue 67, see Fig. IV. The means 70 further embodies upper and lower holder jaws 75, 76, respectively, that grip the heel blanks B, at the top and bottom, in the manner shown in Fig. I. The lower jaw 76 comprises a sector 77—Fig. VI—which engages between ears 78—Figs. I and IV—projecting forwardly from the lower part of the member 69, and it is pivotally supported by a pintle 79. The sector 77 is thus swingable on the pintle 79 for angular adjustment of the jaw 76 relative to the shaft 51, in accordance with graduations shown at 80 in Figs. I and VI, while it is clampable in adjusted positions by a bolt 81 passing through an arcuate slot 82 in the jaw sector piece 77. To the upper straight edge of the sector 77 is secured a face plate 83 having teeth adapted to firmly grip the bottom of the blank B, and a central longitudinal ridge 84—Fig. VII—to fit the aligning groove G in the bottom face of said heel blank. As best shown in Fig. VI, the forward edge of the face plate 83 abuts against an upstanding lug 85 at the frontal portion of the sector 77, while it is secured in place jointly by dowel pins 86 and a screw 87. The upper clamping jaw 75—Fig. I—comprises a piece 88 in the form of a lever which is pivoted on a stud bolt 89 passing, with capacity for up and down adjustment to suit the height of the blanks B, through slots 90 in the side cheeks 68 of the member 69, said slots being located in vertical parallelism with the axis of the cutter 19. To insure against displacement of the bolt 89 in adjusted positions along the slots 90, one of the

side cheeks 68—of the member 69—is finely serrated transversely, as at 91, for co-operation with the correspondingly corrugated face of a nut 92 associated with said bolt, see Fig. V. A bushing 93 surrounding the bolt 89 within the interval between the cheeks 68 of the member 69, acts as a spacer to prevent binding of the upper jaw 75 as the nut 92 is drawn up tight. As shown in Figs. I and IX the upper jaw 75 is equipped with a toothed face plate 94 similar to that of the lower jaw 76, said plate being adjustably secured by means of a bolt 95 which passes through a longitudinal slot and taking into the piece 88. The upper jaw 75 is subject to the upward pull of a tension spring 96 connected to a key grooved screw bolt 97 which is slideable endwise in an aperture in the top of the member 69 but kept from turning by means of a key, and equipped with a spring tension regulating nut 98. A hand screw 99 taking into a threaded aperture in the overhanging portion 100, of the member 69, bears at its lower end upon an anti-friction ball 101 seated in a depression in the top edge of the upper jaw 75.

In employing the machine to shape the heel H of Fig. XII the procedure is as follows:— While the handle 53 of actuating member 52 is in dotted position M Fig. II, the carrier plate 37 with its appendages is bodily swung, by means of handle 42, about its axis 26 away from the cutter 19 into dotted position—as shown in Fig. III—whereby access is afforded to the jaws 75, 76. The hand screw 99 is then backed off to relieve the upper gripping jaw 75 which is at the same time raised automatically through influence of the tension spring 96, so that a heel blank B can be slipped into place on the lower gripping jaw 76, with its groove G engaging the tongue 84 of the toothed face plate 83, and its forward end abutting the projection 85. The upper jaw 75 is thereupon depressed, by means of the hand screw 99, into firm pressure contact with the top of the heel blank B, whereby the latter is tightly gripped between the teeth of the jaw facings 83, 94. The handle 53 is then swung from position M to the right into the dotted position N, and while in this position, the handle 42 is grasped and carrier plate 37 with its appendages swung inward about its axis 26 against abutment 43. The heel blank B is thus passed in a tilted position under the cutter 19 into a tilted position to the right of the same in readiness to be shaped. While holding the carrier plate 37 firmly against the abutment 43, the handle 53 is moved from the dotted position N to the left into the dotted position M Fig. II, whereby the heel blank B is gradually swung through an arc crosswise of the rotating profile cutter 19 with the result that an angular cut is made in said blank to the depth shown in Fig. I. Now incident to the arcuate move-

ment of the heel blank B relative to the cutter 19 about the center of the shaft 51 as an axis, it will be apparent that the breast shank S—Fig. XII, formed as a result of the angular cutting, will be rounded convexly as at R by the edges 20y, 21y of the cutter blades 20 and 21, while the inner face of the heel proper will be concurrently concaved as at C by the edges 20x, 21x through concurrent axial shifting of the shaft 51, as predetermined by the configuration of the cam recess 65 in the plate 64 along which the roller 63 on the actuating member 52 travels. Thus by a single sweep of the heel blank B crosswise of the rotary cutter 19, I am able to effect an angular cut whereof the two surfaces are oppositely curved and merge smoothly into one another so that no subsequent finishing is required. In this connection, it will be particularly remarked that the comparatively deep concavity C at the top of the inner heel face is made possible only through the use of a short radius cutter 19 such as shown, and through relative movement of the blank B in a direction laterally toward and away from the cutting edges 20x, 21x under the influence of the cam plate 64. It is for this reason that the axis of the shaft 51 of the heel blank holder 70 is tilted at an angle, as shown in Fig. I.

With regard to the adjustments provided for, it will be observed that the setting of the lower gripping jaw 76 about the pintle 79 will determine the angular relation of the surface R with respect to the plane of the base of the heel blank B; while the angular relation of surface C, with respect to the plane of the heel blank B, is determined by the angular relation of the cutting edges 20x, 21x to the cutting edges 20y, 21y respectively. Shifting of the holder 70, relative to the supporting head 66, determines the radius of surface R; lowering or raising of slide 31, by means of hand screw 33, determines the thickness of heel shank S; and shifting of the carriage 46, toward or away from the cutter 19, determines the depth of angular cut A. By means of these several adjustments together with the adjustable clamping jaw 75, and its independent adjustable toothed face plate 94 to accommodate clamping of heel blanks B of different height, the machine can obviously be adapted to cutting heels H of all sizes, with differently shaped breast shanks.

The heel H', illustrated in Fig. XIII, is identical with the heel H of Fig. XII—except that its inner face C' is substantially flat instead of being concaved. To produce the heel H'—of Fig. XIII—with the machine of Figs. I, II and III, I simply remove the cam plate 61 and the roller 63, and, during the swinging of the holder 70 about the axis of the shaft 51 by means of the handle 53, apply sufficient pressure thereagainst manually to prevent axial movement of said shaft 51 to the end

that a straight cut is effected as regards the inner face of the heel H' , the heel shanks S being, however, convexly rounded as before.

The modified form of my invention shown in Fig. X is especially adapted for fashioning the H' type of heel—shown in Fig. XIII—with a straight flat inner face, and will be observed as generally similar in construction to the first embodiment with corresponding parts identified by the same reference numerals previously employed, except as to the addition of the subscript " α ". As shown in Fig. X, the blades 20 α , 21 α of the rotary profile cutter 19 α are larger and somewhat differently configured than those of the first described form. By virtue of the straight cutting of the inner heel face in the present connection, axial shifting of the holder 70 α becomes unnecessary, so that the roller 63 and co-operative cam plate 64—of Figs. I and VIII—are here omitted, while the shaft 51 α is set horizontally in the bearing 50 α of the carriage 49 α instead of obliquely as before. The manner of operating the machine of Fig. X is exactly the same as described in connection with the first embodiment as regards placement of a heel blank B in the holder 70 α and manipulation of the carrier plate 37 α against abutment stop 43 α in first positioning the blank B relative to the cutter 19 α and afterwards causing it to be swung crosswise through an arc about the shaft 51 α , as a center, to determine the angular cut and to effect concurrent convexing of the breast shank. The various adjustment features for adapting the machine to fashioning heels of different sizes, etc., are all retained in the modification as will be readily manifest from examination of Fig. X. To avoid rough edges in the finished heels H or H' , the outer rounding is done after fashioning of the angular blights A in accordance with my invention, with the aid of other machinery and in a manner commonly practiced in this art.

While I have described my invention specifically in connection with fashioning of shoe heels H , H' , it is to be understood that the same is adaptable to carrying out other analogous shaping operations through obvious modifications all within the scope of the appended claims. Moreover, by differently shaping the cam plate 64 it will be apparent that many modifications are possible with regard to the shaping of the inner face C or C' of the heel proper.

Having thus described my invention I claim:

1. In a shaping machine for breasting shoe heel blanks, a rotary cutter with cutting edges at an angle to each other and both inclined to the horizontal; holding means for the blanks to be shaped; and means to swing the holding means crosswise of the cutter about an oblique axis substantially parallel to one of the cutter edges to effect fashioning of

continuing curvatures of varying sweep in the frontal face of the blanks with said face rounded concentrically to the swinging axis.

2. In a shaping machine for breasting shoe heel blanks, a rotary cutter with cutting edges at an angle to each other and both inclined to the horizontal; holding means for the blanks to be shaped; and means to move the holding means crosswise of the cutter about an oblique axis substantially in parallelism to one cutting edge of the latter and at the same time laterally toward and away from the other cutting edge to effect fashioning of continuing curvatures of opposing sweep in the frontal surface of the blanks, one portion of said surface being concaved.

3. In a shaping machine for breasting shoe heel blanks, a rotary cutter with cutting edges at an angle to each other and both inclined to the horizontal; holding means for the blanks to be shaped; and means to swing the holding means crosswise of the cutter about an oblique axis substantially parallel to one edge of said cutter, and at the same time toward and away from the other cutter edge to effect fashioning of continuing curvatures of opposed sweep in the frontal face of the blanks, one portion of said frontal face being convexed and the other portion mergingly concaved.

4. In a shaping machine for breasting shoe heel blanks, a rotary profile cutter with cutting edges at an angle to each other and both inclined to the horizontal; holding means for the blanks to be shaped; means to swing the holding means about an oblique axis substantially in parallelism with one edge of the cutter to effect fashioning of continuing curvatures of opposed sweep in the frontal face of the blanks, one portion of said face being rounded; and means enabling angular adjustment of the holding means relative to its swinging axis to correspondingly vary the position in which the blanks are presented to the cutter.

5. In a shaping machine for shoe heels, a rotary profile cutter with cutting edges at an angle to each other and both inclined to the horizontal; holding means for the blanks to be shaped; a carriage sustaining the holding means with capacity for swinging movement about an oblique axis substantially in parallelism with one edge of the cutter to effect fashioning of continuing curvatures of varying sweep in the frontal face of the blanks, one portion of said face being convexly rounded to provide the breast shank; and means to concurrently shift the axis of the holder endwise in the carriage to predetermine concaving of the other portion of the face to form the heel front.

6. In a shaping machine for shoe heels, a profile cutter comprising parallel blades with cutting edges at an angle to each other and both inclined to the horizontal; holding

means for the blanks to be shaped; a carriage sustaining the holding means with capacity for swinging movement about an oblique axis substantially in parallelism with one edge of 5 the cutter to effect fashioning of continuing curvatures of opposed sweep in the frontal part of the blanks with one portion thereof convexly rounded; and a pivoted support for said carriage whereby the carriage and its 10 appendages are swingable bodily horizontally away from the cutter to facilitate mounting of the blanks in the machine.

7. In a shaping machine for shoe heels, a rotary profile cutter comprising parallel 15 blades with cutting edges at an angle to each other and both inclined to the horizontal; holding means for the blanks to be shaped; a carriage sustaining the holding means with capacity for swinging movement through an 20 arc crosswise of the cutter to effect fashioning of continuing curvatures of opposed sweep in the frontal part of the blanks with one portion thereof convexly rounded; a pivoted support for said carriage whereby the 25 carriage and its appendages are horizontally swingable away from the cutter to facilitate mounting of the blanks in the machine; and means whereby the plane of the support may 30 be vertically adjusted relative to that of the cutter.

8. In a shaping machine for shoe heels, a rotary profile cutter comprising parallel blades with cutting edges at an angle to each other and both inclined to the horizontal; holding means for the blanks to be shaped including a pair of cooperating gripping jaws 35 capable of separate adjustment with maintenance of parallelism between them to accommodate blanks of different sizes as well as for presentation of the blanks in different angular positions to the cutter; and means to simultaneously move the holding means arcuately and slidably relative to the cutter in shaping the blanks.

45 9. In a shaping machine for shoe heels, a rotary profile cutter comprising parallel blades with cutting edges at an angle to each other and both inclined to the horizontal; holding means for the blanks to be shaped 50 including a gripping jaw with capacity for angular adjustment in respect to the cutter, a pivotally-mounted spring influenced cooperating gripping jaw, means to actuate the pivoted jaw incidental to placement of the 55 blanks, and means enabling positional adjustment of the pivot with maintenance of parallelism as between the jaws in accommodating blanks of different sizes; and means to simultaneously move the holding means 60 arcuately and slidably relative to the cutter in shaping the blanks.

10. In a heel-shaping machine, the combination of a cutter mounted for rotation in a definite plane and so shaped as to conform 65 to the breast and shank portions of the heel

to be produced, means for carrying a heel blank over an arcuate path across the course of rotation of the cutter, the arcuate path of the heel blank defining a plane which is disposed at an angle relative to the axis of rotation of the cutter, for shaping the breast and rounding the shank portion of the heel simultaneously, the plane defined by such arcuate path being also angularly disposed relative to the longitudinal axis of the blank, and means for momentarily advancing the heel blank toward the cutter longitudinally of the axis about which the blank moves in its passage over said arcuate path.

11. In a heel-shaping machine, the combination of a main frame, a cutter mounted for rotation in a definite plane in said main frame, a swinging frame pivotally mounted on said main frame, a bearing on said swinging frame, a spindle rotatably mounted in said bearing, a chuck on one end of said spindle, a handle on the opposite end of said spindle for rocking said chuck, a projection on said handle, and lugs on said bearing co-operating with the projection on the handle to limit the rotary movement of the chuck.

12. In a heel-shaping machine, the combination of a main frame, a cutter mounted for rotation in a definite plane in said main frame, a swinging frame pivotally mounted on said main frame, a bearing on said swinging frame, a spindle rotatably mounted in said bearing, a chuck on one end of said spindle, a handle on the opposite end of said spindle for rocking said chuck, a plate on said bearing, a roller carried by said handle and riding on said plate, said plate having a concavity in the path of said roller permitting momentary movement of said chuck in a direction longitudinally of its spindle toward the cutter.

13. In a heel shaping machine, the combination of a cutter mounted for rotation about a vertical axis and adapted to conform to the breast and shank of the heel to be produced, means for moving a heel blank over an arcuate course relative to the rotative confines of the cutter, said arcuate course being at an acute angle with respect to the axis of rotation of the cutter and at an obtuse-angle relative to the plane of rotation of said cutter, said means for moving a heel blank being pivoted on a vertical axis to be swung toward and away from the cutter to permit loading and unloading, and both of said axes of movement being disposed in a common vertical plane when the heel blank moving means is swung around toward the cutter.

14. In a heel-shaping machine, the combination of a cutter mounted for rotation about a vertical axis and adapted to conform to the breast and shank of the heel to be produced, means for moving a heel blank over an arcuate course relative to the confines of rotation of the cutter, said arcuate course being at

an acute angle with respect to the axis of rotation of the cutter and at an obtuse-angle relative to the plane of rotation of the cutter, said means for moving a heel-blank being pivoted on a vertical axis to be swung toward and away from the cutter to permit loading and unloading, both of said axes of movement being in a common vertical plane when the heel blank moving means is swung around 10 toward the cutter, and means for momentarily advancing the heel blank toward the cutter during its rotative progress over the arcuate course aforesaid.

In testimony whereof, I have hereunto signed my name at Philadelphia, Pennsylvania, this 21st day of October, 1927.

OSCAR L. SCHEHL.
